UNITED STATES PATENT OFFICE

THOMAS DALTON, OF CHICAGO, ILLINOIS, ASSIGNOR TO W. J. DENNIS & COMPANY, OF CHICAGO, ILLINOIS, A CORPORATION OF ILLINOIS

BRUSH AND MOP HOLDER

Application filed November 5, 1927. Serial No. 231,324.

This invention pertains to the general class of devices which are attached to brushes and mops, and particularly to a holder or handle for said brushes and mops. An object of 5 the applicant's invention is the production of a holder for brushes and mops that will facilitate the use of same for all purposes. A further object of applicant's invention is the production of a holder for brushes and 10 mops that is readily attached and detached, the same comprising a small number of parts, simple and durable in construction, of low cost and highly satisfactory for its intended purposes. Many other objects and advantages 15 of the construction herein shown and described will be obvious to those skilled in the art from the disclosure herein given.

In the preferred form of the invention, the applicant provides a handle with means 20 whereby the same may be readily attached to a mop or brush. The attachment of a handle to a brush or mop has advantages which are readily appreciated by persons accustomed to use same. The handle may be of any 25 length desired. Applicant's novel invention not only permits the use of a brush or mop in hot, strong, or other solutions deleterious to the hands, but is also advantageous in reaching places not ordinarily accessible. It 30 is readily apparent, however, that the holder may be secured in a stationary position, thus holding the brush rigid, and the article brought up to the brush.

To this end my invention consists in the 35 novel construction, arrangement and combination of parts herein shown and described, and more particularly pointed out in the claim.

In the drawings, wherein like reference 40 characters indicate like or corresponding parts:

Fig. 1 is a top plan view of the device attached to a brush;

Fig. 2 is a front elevation of same;

Fig. 3 is a section on line 3—3 of Fig. 1;

Fig. 4 is a section taken on line 4—4 of Fig. 3;

Fig. 5 is a top plan view of a different form of the invention, showing applicant's novel holder applied to a mop;

Fig. 6 is a section taken on line 6—6 of Fig. 5; and

Fig. 7 is a section taken on line 7—7 of Fig. 5.

Referring now to the drawings, 1 is a brush 55 which is composed of a base 2 for holding the bristles 3. The base 2 has longitudinal grooves 4 in the longitudinal edges thereof. Secured to the base 2 of the brush is the holder 5 which is composed preferably of a handle 6, a stationary clamping member 7 and a movable clamping member 8. The handle 6, in the preferred embodiment, is of square or rectangular cross-section at one end thereof as clearly shown at 9. The extreme end 60 is beveled as shown at 10, the beveled portion contacting the upper surface of the base 2. The stationary clamping member 7 is preferably a stamping and made from sheet metal. However, it is obvious that the member 7 may be formed by other means, such as casting, etc., or the handle 6 and member 7 may be stamped or cast integral thus forming 65 one piece.

The stationary clamping member 7 is preferably formed with a shank portion 11 which is secured to the handle 6 by any convenient means such as a screw 12. In the preferred embodiment, the shank portion 11 is formed at its edges with flanges 13 which contact 70 the side faces of the rectangular portion 9 of handle 6. The member 7 is formed with a boss 14. The boss 14 is apertured to accommodate the movable clamping member 8 which passes through the aperture 15 in the 75 handle 6, as clearly shown in Fig. 3. The lower end 16 of movable clamping member 8 is formed more or less U-shape and engages 80 one edge of the brush or mop. The other end 17 of the member 8 is threaded and provided 85 with a wing nut 18.

Returning now to the stationary clamping member 7, at the lower end of the shank portion 11 is formed the gripping portion 19 which is preferably wider than the shank portion 11 and makes an angle therewith as shown at 20. The outer end of the gripping portion 19 is curved downward as shown at 21 and ends in a more or less straight portion 22 which engages the longi- 100

tudinal edge of the brush or mop in the groove 4. It is readily seen that in order to secure the handle 6 to the base 2, it is merely necessary to tighten the wing nut 18.

Referring now to Figs. 5, 6 and 7, the base 2' is formed with a longitudinal groove 23 in the lower face thereof. In the outer ends of the groove 23 and extending through the base of the brush are apertures 24 which accommodate a U-bolt 25 provided with wing nuts 26. The U-bolt 25 holds the mop 27 in groove 23, as clearly shown in Figs. 6 and 7, respectively.

A highly efficient, novel and compact brush and mop holder is thus provided which is highly satisfactory for its intended purpose. It is readily apparent that the use of this device is not limited to a scrub brush, but may be used with any type of brush or mop, or other similar device.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

In a device of the kind described, a one-piece stationary clamping member, and a one-piece J-shaped movable clamping member, said stationary member constructed to contact three sides of a handle to prevent side play of the member and further formed into a flared channel shaped gripping jaw of substantially V-shaped cross section, running substantially at right angles to the longitudinal axis of the stationary member, said movable clamping member arranged angularly through the stationary clamping member with the hooked part of the J adapted to engage the back edge of a base top substantially at its mid-point, means on said movable clamping member for urging the assembly together, an inclined boss formed on the base of said stationary member, whereby the means on said movable clamping member may have a substantially flat bearing surface.

In testimony whereof, I have hereunto signed my name.

THOMAS DALTON.
